CLAIM

(22) Filed: **Oct. 5, 2015**

What is claimed is the ornamental design for an electrical junction box, substantially as shown and described.

(51) LOC (11) Cl. **13-03**

DESCRIPTION

(52) U.S. Cl.

USPC **D13/152**

(58) **Field of Classification Search**

FIG. 1 is a top, side perspective view of an electrical junction box of our new design;

USPC D13/152, 119, 147, 156, 177, 184, 107,

FIG. 2 is another top, side perspective view thereof;

D13/108, 110, 123, 133, 137.1–137.4,

FIG. 3 is a top plan view of the electrical junction box of FIG. 2;

D13/138.1–138.2, 139.1–139.8, 153, 154,

FIG. 4 is a front elevation view thereof, the rear view being identical;

D13/146, 158; D8/350, 351–353;

FIG. 5 is a right side view thereof, the left side view being identical;

D25/119, 127, 134, 48.4; D26/74

FIG. 6 is a bottom plan view thereof;

(Continued)

FIG. 7 is a front, right, bottom perspective view thereof;

(56) **References Cited**

FIG. 8 is a top plan view of the electrical junction box of FIG. 1;

U.S. PATENT DOCUMENTS

FIG. 9 is a front elevation view thereof;
